UNITED STATES PATENT OFFICE.

WILLIAM C. LEA AND JOSEPH C. GEORGE, OF LOS ANGELES, CALIFORNIA.

SASH-OPERATING DEVICE.

1,213,508.

Specification of Letters Patent. Patented Jan. 23, 1917.

Application filed January 18, 1916. Serial No. 72,870.

To all whom it may concern:

Be it known that we, WILLIAM C. LEA and JOSEPH C. GEORGE, both citizens of the United States, residing at Los Angeles, in the county of Los Angeles and State of California, have invented a new and useful Sash-Operating Device, of which the following is a specification.

Our invention relates to windows, and more particularly to casement windows, but is applicable to any form of window or transom which is hinged along one edge to swing either in or out.

The principal object of our invention is to provide a sash operating device for such a window of simple form and construction.

One of the principal objections to casement windows is the difficulty of operating them where curtains or screens are used, particularly in the latter case. In the form shown, in which the invention is applied to a casement window which swings outwardly, it is necessary to place the screen inside, thereby shutting off access to the window proper without disarranging the window shade, curtains and opening the screen.

A further object of our invention is to provide an operating device by means of which a window of the character described placed on the outside of the opening may be opened or closed without disarranging the shade or curtains, and without opening the screen. That is, the window is entirely operated in so far as opening or closing is concerned from the inside of the room.

A further object is to provide a sash operating device of the character described which imparts the maximum range of movement to the sash so that the same may be swung at right angles to the sash when in closed position thereby giving a full window opening.

A further objection of casement windows lies in the difficulty of gaining access to the outer side for cleaning purposes, and it is a further object of our invention to provide a casement window in which the sash can be so turned that access is had to both sides thereof.

A further object of our invention is to provide a sash operating device having the above characteristics which will have a few parts, and which will be ornamental in appearance, and take up comparatively little space in its installation.

Further objects and advantages will be made evident hereinafter.

In the drawings which are for illustrative purposes only: Figure 1 is an elevation of a casement window equipped with our invention. Fig. 2 is a similar view on a larger scale, a portion of the window being broken away and shown in section to better illustrate our invention. Fig. 3 is a plan view shown in section on a plane represented by the line x^3-x^3 of Fig. 1 looking in the direction of the arrows, various positions of the sash being shown in dotted or broken lines to better illustrate the various positions of the window. Fig. 4 is a section on a plane represented by the line x^4-x^4 of Fig. 3, this plane being viewed in the direction of the arrows. Fig. 5 is a perspective view of the various parts of the mechanism slightly separated to better show their relation, and Fig. 6 is a plan view showing the sector and latch, this plan being viewed from below. Fig. 7 is a plan view of the swinging arm at the pivot thereof taken from above.

In these drawings a sash 11 is provided, this sash fitting inside a casement 12, the casement being formed of a top member 13, side members 14, and a bottom member 15. A window sill 16 is located inside the casement at the lower end thereof, this window sill being attached to a spacer 17 and to an apron 18, the parts 12 to 18 inclusive being secured together to form a permanent stationary structure. Inside the window may be placed a screen 20, this screen being secured inside vertical straps 20' which are secured to the inside of the members 14, forming a unitary structure therewith, or the screen may be hinged at one side thereof and adapted to swing inwardly into the room, such construction being common and well known.

Secured to the top and bottom of the sash 11 are sash pivot plates 21, these sash pivot plates having a cylindrical portion 22 which is set into the sash, and a flat portion 23 which is secured to the sash through holes 24 by screws 25. Brace pivot plates 26 are secured by means of screws 27 to the top and bottom of the sash, the brace pivot plates having holes 28 therein. The sash pivot plates 21 are provided with an opening 30 in which a slide pivot pin 31 turns freely. The slide pivot pin 31 is secured to a slide 32, the slide 32 sliding freely inside in a

sheet metal guide 33, the guide 33 being in box form as shown in Fig. 4. The guide 33 is at the bottom of the casement 12. The slide 32 is restrained from sliding in the 5 guide by means of a flat spring 35, this spring being secured to the slide 32 by means of rivets 36. A catch pin 37 is secured in the flat spring 35 and projects through the slide 32 dropping into a small hole 38 formed in the guide 33 in such a position as to hold the 10 slide 32 at its extreme left hand position as shown in the drawings.

A swinging arm 40 is provided in the bottom of the window, this arm consisting of 15 a brace portion 41 and an operating portion 42. A swinging arm 43 is also provided in the top of the window, the swinging arm 43 being similar to the swinging arm 40 with the omission of the operating portion 20 42. The portions 41 and 42 of the arm 40 are connected by means of a box 45, this 25 box being of sufficient size to allow the end of the slide to fit therein, and having a lower portion 46 adapted to extend under the bottom of the slide when it is in its normal position therein. A locking slot 47 is provided in the top of the box 45 into which the slide pivot pin 31 fits and slides.

A casement pivot plate 50 is rigidly secured to the casement by means of screws 30 51, this casement pivot plate carrying a casement pivot pin 52, this casement pivot pin 52 extending up and engaging an opening 53 in the lower portion 46 of the box 45, so that the swinging arm is restrained to 35 turn about the pin 52 which is rigidly secured in the casement by means of the casement pivot plate 50.

On the outer end of the brace portion 41 40 of the swinging arm 40 is located a brace pivot pin 60, this pin passing through the hole 28 in the brace pivot plate 26, and having an enlarged head 61 so that it is retained in the hole 28 turning freely therein. 45 On the outer end of the operating portion 42 of the swinging arm 40, which swings in an opening below the window sill 16, is located a latch 65, this latch consisting of a flat piece of steel bent at right angles as best 50 shown in Fig. 5, and having a large end 66. The latch 65 is provided with an L shaped slot 67, this slot sliding on pins 68 secured in the operating portion 42 of the arm 40. A spring 69 engages small projections 55 formed on the latch 65, and on a bent end 70 which is formed on the operating portion 42 of the swinging arm 40. The end 66 of the latch 65 is of such a shape, and is so located that it engages a plurality of notches 60 71, these notches being formed in a sector 72 secured below the window sill 16 in such a position as to be out of sight and fully protected by the window sill 16. The upper 75 swinging arm 43 is provided with its equivalent structure to the lower swinging arm

41, with the exception of the part 42, and the parts 66 to 72 inclusive.

The method of operation is as follows: When used to open and close the window the slide pivot pin 31, and the casement pivot 70 pin 52 are in line as shown in Fig. 3, the slide 32 being restrained in this position by the catch pin 37, and the window being swung open or closed by means of the operating portion 42, the window being locked 75 in any position by means of the end 66 of the latch 65 which engages the notches 71 in the sector 72. This latch 65 can be disengaged from the sector 72 by a pressure of the fingers against the spring 69, and if 80 desired the latch 65 can be locked in its disengaged position by moving it sidewise into the dotted position shown at "A" in Fig. 6, so that the window can be opened or closed, or moved to any of its positions as hereinafter explained without having to pay any particular attention to the latch 65. In the ordinary opening and closing of the window it moves from its closed position into its open position as shown at "B" in 85 Fig. 3 simply by turning the window by means of the operating portion 42 of the swinging arm 40, the swinging arm 43 moving in synchronism therewith. It will be noted that the operating portion 42 extends into the room under the window sill 16, thus allowing the window to be operated without interfering with the screen 20, or with any shades or curtains which may be hanging inside the window, this being the 90 ordinary operation thereof. It will further be noted that the window may be locked in its open or closed position by means of the sector 72.

When it is desired to clean the window, 105 the window is opened to its full position as shown at "B" in Fig. 3, the screen 20 being also opened. The end of the flat spring 35 is then raised lifting the catch pin 37 out of the hole in the guide 33, this allowing the 110 slide 32 to be moved to the right in the guide 33. No spring corresponding to the spring 35 is provided in the top of the window so that the operator has to manipulate only the single spring 35 at the bottom. 115 With the window in the position at "B" in Fig. 3, the box 45 is turned around so that the locking slot 47 is at right angles to the position shown in Figs. 3 and 5, it then being possible to move the slide 32, pulling the 120 slide pivot pin 31 out of the locking slot 47 which in that position has its long direction parallel to the slot in the guide 33. The slide 32 can then be moved over to the position shown at "C" in Fig. 3, the window 125 moving over into the position shown at "D" in Fig. 3, the brace portion 41 of the swinging arm 40 assuming the position "E" shown in that figure, and serving as a brace to hold the window in the position "D." With 130

the window in the position "D" it is possible to gain access to what is the outer side of the window when closed, so that with the sash in this position it is possible to 5 clean this outer side from the inside of the window.

When it is desired to return the window to its original position the inner end of the sash is pushed to the left as shown in Fig. 10 3, the window being moved in the position "B," the catch pin 37 snapping into the hole in the guide 33 automatically so that the parts are locked in the operating position, or in the position shown in Figs. 1, 2, 3 15 and 4.

We claim as our invention:—

1. A window structure comprising a casement, a sash in said casement, a movable pivotal connection between said casement 20 and said sash, a swinging arm pivotally mounted on said casement, means for pivotally connecting the outer end of said arm to the sash, said arm being adapted to engage and hold said movable pivotal connection stationary during the swinging movement of said arm to open the sash, and means for locking the inner end of said swinging arm.

2. A window structure comprising a 30 casement, a sash in said casement, a movable pivotal connection between said sash and said casement, a swinging arm pivotally mounted in said casement and having its outer end pivotally connected to said sash, 35 said arm having engaging means for holding said movable pivotal connection directly over the pivotal connection of the swinging arm and casement during the opening movement of the sash, and permitting lateral 40 movement of said movable pivotal connection when the sash has reached its open position.

3. A window structure comprising a casement, a sash fitting inside said casement, 45 guides secured inside said casement at the top and bottom of the window opening, said guides having grooves cut therein, slides so shaped that they fit inside said grooves and slide freely therein, a slide 50 pivot pin secured to each of said slides and projecting into the sash opening of said casement, sash pivot plates secured to the top and bottom of said sash and having an opening therein into which said slide pivot 55 pin projects, detachable catch means for locking said bottom slide in one extreme position, casement pivot plates secured to said casement at the top and bottom of the sash opening, casement pivot pins secured to 60 said casement pivot plates in such a position that they are on the same axis as the slide pivot pins when said bottom slide is locked in its extreme position, swinging

arms pivoted on said casement pivot pins at the top and bottom of said sash, brace pivot 65 plates secured to the top and bottom of said sash, and brace pivot pins each secured to the outer end of one of said swinging arms and engaging and turning in one of said brace pivot plates, said lower swinging 70 arm having a locking slot formed therein, said locking slot being so located and shaped that said slide pivot pin is locked therein whenever the sash is partly or wholly closed. 75

4. A window structure comprising a casement, a sash in said casement, pivotal means for said sash at the top and bottom thereof movably mounted in said casement, and a swinging arm pivotally mounted in said 80 casement for swinging said sash, said arm having a locking slot adapted to engage the sash pivotal means at the bottom of the sash.

5. A window structure comprising a 85 casement, a sash in said casement, pivot plates secured to said sash at the top and bottom thereof, guides secured to said casement at the top and bottom thereof, a slide in each guide, pins on said guides engaging 90 the respective pivot plates, means on one of said slides for releasably engaging its respective guide, an arm pivotally mounted intermediate its length on said casement, and means for pivotally connecting the 95 outer end of said arm to said sash, said arm having a locking slot therein adapted to receive the pin on one of said slides.

6. A window structure comprising a casement, a sash in said casement, pivotal means 100 for said sash movably mounted in said casement, an arm pivotally mounted in said casement provided with a locking slot in the pivotal axis of said arm adapted to engage the sash pivot means, and means on 105 the end of said arm for pivotally engaging said sash.

7. A window structure comprising a casement, a sash in said casement, pivotal means for said sash movably mounted in said casement, an arm pivotally mounted in said casement provided with a locking slot in the pivotal axis of said arm adapted to engage the sash pivot means, means on the end of 110 said arm for pivotally engaging said sash, means for fixing said arm in a series of 115 angular positions said means consisting of a notched sector mounted on said casement, and releasable means carried on said arm adapted to engage the notched portion of 120 the segment.

In testimony whereof, we have hereunto set our hands at Los Angeles, California, this 11th day of January, 1916.

WILLIAM C. LEA.
JOSEPH C. GEORGE.
